United States Patent Office

Des. 218,843

Patented Sept. 29, 1970

218,843

PLATTER

Edwin G. Melich, Chicago, Ill., assignor to Melco Foundry & Manufacturing Company, a corporation of Illinois

Filed Jan. 6, 1969, Ser. No. 15,230

Term of patent 14 years

Int. Cl. D7—01

U.S. Cl. D44—10

FIG. 1

FIG. 2

FIG. 3

FIG. 4

FIG. 1 is a top plan view of a platter showing my new design;

FIG. 2 is a bottom plan view;

FIG. 3 is a sectional view on line 3—3 of FIG. 1; and

FIG. 4 is a sectional view on line 4—4 of FIG. 2.

The dotted lines indicate portions of the platter which do not embody the design, and are environmental thereto.

I claim:

The ornamental design for a platter, as shown and described.
